United States Patent Office

Des. 207,410
Patented Apr. 11, 1967

207,410

APPETIZER SCOOP OR THE LIKE

Leo F. Wildgen, Minneapolis, Minn., assignor to Arthur Salm, Inc., Chicago, Ill., a corporation of Illinois

Filed May 2, 1966, Ser. No. 2,112

Term of patent 14 years

(Cl. D44—29)

FIG. 1 is a perspective view of an appetizer scoop incorporating my new design;

FIG. 2 is a front elevational view thereof;

FIG. 3 is a scoop end view thereof;

FIG. 4 is a handle end view thereof; and

FIG. 5 is a rear elevational view thereof.

I claim:

The ornamental design for an appetizer scoop or the like, substantially as shown.
